PACKAGING CONTAINER FOR FOOD OR THE LIKE

Paul A. Weller, Waukegan, Ill.
(Rte. 1, Box 66A, Union Grove, Wis. 53182)

Filed Feb. 9, 1972, Ser. No. 225,029

Term of patent 14 years

Int. Cl. D9—03

U.S. Cl. D9—219

FIG. 1

FIG. 3

FIG. 1 is an isometric view of a packaging container for food or the like showing my new design, the sides not shown being the same in appearance as the side shown;

FIG. 2 is an elevational view; and

FIG. 3 is a top plan view thereof.

I claim:

The ornamental design for a packaging container for food or the like, substantially as shown and described.
